UNITED STATES PATENT OFFICE

108,999

DESIGN FOR A DRESS ENSEMBLE

Ann La Placa, Corona, Long Island, N. Y.

Application February 23, 1938, Serial No. 75,331

Term of patent 3½ years

To all whom it may concern:

Be it known that I, Ann La Placa, a citizen of the United States, residing at 100-04 Spruce Avenue, Corona, Long Island, in the county of Queens and State of New York, have invented a new, original, and ornamental Design for a Dress Ensemble, of which the following is a specification, reference being had to the accompanying drawing constituting a part thereof.

Fig. 1 is a front view of a dress ensemble showing my design.

Fig. 2 is a rear view thereof.

Fig. 3 is a front view of the dress section of the ensemble shown in Fig. 1.

Fig. 4 is a rear view of Fig. 3.

I claim:

The ornamental design for a dress ensemble substantially as shown.

ANN LA PLACA.
